CLAIM

The ornamental design for a shed, as shown and described.

DESCRIPTION

FIG. 1. is a perspective view of a shed showing the design; FIG. 2. is a second perspective view thereof;

FIG. 3. is a front elevation view thereof;

FIG. 4. is a rear elevation view thereof;

FIG. 5. is a left side elevation view thereof;

FIG. 6. is a right side elevation view thereof;

FIG. 7. is a top plan view thereof; and,

FIG. 8. is a bottom plan view thereof.

The broken lines in the drawings depict portions of the shed that form no part of the claimed design.

1 Claim, 8 Drawing Sheets
